Inventor

F. E. Lumley.

Attorney

UNITED STATES PATENT OFFICE.

FRANK E. LUMLEY, OF OMAHA, NEBRASKA.

VALVE.

Application filed February 23, 1924. Serial No. 694,761.

To all whom it may concern:

Be it known that I, FRANK E. LUMLEY, a citizen of the United States, residing at Omaha, in the county of Douglas and State 5 of Nebraska, have invented certain new and useful Improvements in Valves, of which the following is a specification.

The present invention relates to valves and has more particular reference to that type 10 which is shown as a release valve in suction or vacuum type lines.

An object of this invention is to provide certain improvements in the release valve which is shown in my Patent No. 1,455,116 15 granted May 15, 1923. It has been found that the spring shown in the valve as disclosed by my prior patent is free to rotate and become loose by the automatic working of the valve, and it is one of the objects of 20 this invention to prevent this unscrewing or rotation of the valve and to provide a screen to prevent dirt, dust and other accumulations from entering the valve while the same is open for the admission of air.

Another object of the invention is to provide means for supplying a lubricant to the 25 valve plunger to insure the tight seating of the plunger when the valve is closed so as to maintain an air tight joint between the valve and its seat and to prevent undue wear upon the relatively moving parts.

The invention has for a further object to 30 provide a valve possessing the above characteristics and which at the same time may be economically manufactured and easily 35 and quickly assembled and installed, and one which may be used in connection with various other vacuum or suction systems than were disclosed in my prior patent.

With the foregoing and other objects in 40 view, the invention will be more fully described hereinafter, and will be more particularly pointed out in the claims appended hereto.

In the drawings, wherein like symbols 45 refer to like or corresponding parts throughout the several views,

Figure 1 is a vertical section taken 50 through a release valve constructed according to the present invention.

Figure 2 is a top plan view thereof.

Figure 3 is a transverse section through the upper end of the valve taken substantially on the line 3—3 in Figure 1.

Figure 4 is a detail plan view of the dust 55 screen employed.

Figure 5 is a top plan view of the valve piston or plunger employed.

Figure 6 is a side elevation of the same.

Figure 7 is a plan view of the oil pad used, 60 and

Figure 8 is a plan view of the packing ring against which the valve is adapted to seat.

Referring to the drawing 10 designates 65 the valve casing or cylinder which is of suitable diameter and length and which is externally threaded upon its lower end as at 11 to be screwed into a tank, a pipe or any other suitable element of a vacuum or 70 suction pipe line. The cylinder 10, at its intermediate portion, is reduced in diameter to provide a neck 12 and a seating shoulder 13 at the juncture between the body of the cylinder 10 and the neck 12 the shoulder 13 75 being annular and facing downwardly.

The upper end of the neck 12 is enlarged to provide a cylindrical cup or receptacle 14 which forms an upwardly facing shoulder 80 15 adapted to support a dust screen 16 which extends over the upper end of the neck 12 and excludes dust, dirt and other accumulations from entering the neck and the cylinder. The screen 16 supports an annular pad 17 of absorbent material adapted to be 85 saturated with oil or the like so that air passing downwardly through the neck 12 is first charged with a quantity of oil and carries the oil down through the screen 16, neck 12 and in the body of the cylinder 10. 90

Fitting in the cylinder is a valve head or plunger 18 in the form of a cylindrical block provided on its lower end with a seating flange 19 of greater diameter than the neck 12 and adapted to seat upwardly against the 95 shoulder 13 when the block 18 is raised. The flange 19 is adapted to carry a compression ring 20 of rubber or other suitable material which may be impinged against the shoulder 13 and compressed for sealing the 100

passage about the lower end of the block 18. As the plunger or valve head 18 is moved downwardly it is designed to increase the size of the passage or opening through the valve, and for this purpose, the cylindrical block or valve 18 is provided with vertical flutes 21 which taper downwardly and which open at their larger base ends through the top of the block. By these flutes with their flaring upper ends, the further down the block 18 is advanced, the wider is the passage about the shoulder 13 for admitting air to the lower end of the cylinder 10.

The cup 14 of the cylinder carries an upstanding frame 22 which provides side rails upon which slide the oppositely extending forks 23 of an adjusted bar 24 forming the upper portion of a spring receiving frame 25, the frame being rectangular and extending downwardly from the bar 24 within the frame 22. The bar 24 has a threaded stem 26 upon its upper side which projects through the top of the frame 22 and which receives an adjusting nut 27, preferably of the wing type for raising and lowering the frame 25.

As shown in Figures 1 and 3, a frame 25 carries therein a cross head 28 which is forked at opposite ends to fit sides of the frame 25 so as to guide the cross head 28 in its vertical movement. The cross head 28 is mounted upon the upper end of a valve stem 29 which is screwed or otherwise suitably secured in the top of the valve or block 18 so that the cross head 28 moves with the block. A helical spring 30 is placed about the valve stem 29 within the frame 25 and between the bottom of the frame and the under side of the cross head 28 for yieldingly urging the block 18 upward.

The spring 30 therefore merely maintains the valve 18 closed and the tension on the valve may be varied by raising the cross bar 24 to more or less compress the spring 30. It will be noted that the cross head 28 cannot turn in the frame 25, and the frame 25 cannot turn in the upper frame 22 on account of the forks 23 of the cross bar 24 slidably fitting the side portions of the frame 22.

In operation, when the device is in use the winged nut 27 is turned down upon the threaded stem or rod 26 to an extent sufficient to place the spring 30 under the desired tension. When suction in the lower end of the cylinder 10 becomes sufficient to overcome the tension of the spring 30, the valve 18 is drawn outwardly and the air is admitted through the cup 14 past the valve 18 into the suction line to an extent dependent upon the proportion of downward movement of the valve 18. The air in passing downwardly through the cup 14 first is drawn through the relatively

large opening in the annular pad 17 and absorbs a quantity of the oil contained in the pad and carries this oil downwardly through the screen 16 and through the fluted opening 21 to the compressible gasket 20 and valve seat 13. The screen 16 catches particles of dust and other foreign substance and prevents the same from reaching the valve seat.

The compressible ring or gasket 20 is thus oiled and a film of oil is maintained upon the valve seat 13 and the ring so that the spring 30 is sufficient for maintaining a tight sealing of the valve 18 against the shoulder 13.

I do not wish to be restricted to the size, form, and proportions of the various parts, and obviously changes could be made in the construction herein described without departing from the spirit of the invention, it being only necessary that such changes fall within the scope of the appended claims.

What is claimed is:

1. In a release valve for vacuum systems, a cylinder having a downwardly facing shoulder, a valve in the cylinder having an upwardly facing seating portion, a frame carried by the casing, an inner frame slidably mounted on the outer frame and held thereby from turning, a cross head mounted in the inner frame arranged to slide therein and held thereby from turning, a spring in the inner frame between the same and the cross head, and means for raising and lowering the inner frame upon the outer frame.

2. In a release valve for vacuum cleaning systems, a casing, an upwardly seating valve mounted in the casing, a cross head connected to the valve, a spring engaging beneath the cross head, an inner frame enclosing the spring and engaging the other end thereof to exert pressure against the cross head for seating the valve, an outer frame, means connecting the inner and outer frames for tensioning the inner frame against the spring, and means upon the cross head and the inner frame for maintaining said cross head and said inner and outer frames from relative turning.

3. In a release valve, a casing enlarged at its upper and lower ends, a valve block mounted in the intermediate portion of the casing and having an enlarged flange engaging in the larger lower end of the casing and adapted to seat upwardly thereagainst for sealing the casing against downward passage of air, a screen seated in the upper end of the casing for screening air passage therethrough, an oil pad mounted in the upper end of the casing on the screen for supplying oil to the air passing outwardly through the casing, an outer frame fixed to the casing, an inner frame slidably upon

the outer frame and held from turning therein, a cross head in the inner frame held from turning therein, a connection between the cross head and said valve block, and a
5 spring between the cross head and the inner frame for normally elevating the valve block.

In testimony whereof, I have affixed my signature in presence of two witnesses.

FRANK E. LUMLEY.
